CARTON

Raymond Stone, New York, N. Y., assignor to
 Self-Locking Carton Co., Chicago, Ill., a corporation of Illinois

Application May 6, 1933, Serial No. 669,652

8 Claims. (Cl. 229—29)

The present invention relates to cellular cartons of the type produced from cardboard or similar materials and has particular reference to improvements in cartons of the type described in 5 5 Troyk patent, No. 1,766,155, issued June 24, 1930.

A particular object of my invention is to provide a cushion bottom carton in which is employed a small quantity of cardboard.

An additional object is to provide a cushion 10 bottom carton of the type described which may be folded into flattened or collapsed condition in an easier manner than has been customary heretofore.

A still further object is the provision of an egg 15 carton having a bottom section of substantially inverted V-shape and cross partitions which are secured to the bottom section and being higher adjacent one wall of the carton than adjacent the other wall thereof.

These and other objects will be apparent to 20 one skilled in the art from a consideration of the following description of a preferred embodiment of my invention and by reference to the accompanying drawings, in which

Fig. 1 is a perspective view of a carton constructed in accordance with my invention;

Fig. 2 is a longitudinal section taken through the center of the carton, as represented by the line 2—2 of Fig. 3;

Fig. 3 is a cross sectional view of the carton taken along line 3—3 of Fig. 2;

Fig. 4 is a plan view of the carton shown in collapsed or flattened condition;

Fig. 5 is a plan view of a modified form of the 30 carton in which the front edges of the cross partitions are lower than the rear edges and shows the cross partitions in horizontal position preliminary to being rotated into vertical position for erection of the carton; and

Fig. 6 is a cross sectional view taken along line 35 3—3 of Fig. 5 and shows the carton completely erected.

The cellular carton described in the aforesaid 40 Troyk patent consists of front and rear walls, cross partitions secured to said walls, and a bottom section of substantially greater width than the width of the cross partitions, said bottom being pressed upwardly along its central portion into substantially inverted V-shape and secured to 45 the cross partitions by means of hooks thereon. Due to the substantially greater width of the bottom section than the cross partitions it is necessary to fold the Troyk carton along the score lines centrally of the cross partitions and the 50 bottom section. In manufacture, the blank is

properly cut and scored, then folded along the scoring in the center of the bottom section, again folded along the score in the cross partitions and the attaching strip secured to the free end in the cross partitions is glued to the rear wall. It will be seen that this process of manufacture involves a number of folding operations and that the gluing operation must be effected beneath superimposed paper.

In accordance with my invention, the objections 5 10 to the method of manufacture of the Troyk carton are eliminated by proportioning the parts of the carton in such a manner as to permit the carton to be manufactured by a simple folding operation. Also, my carton involves the saving 15 of considerable quantities of material. More specifically, the carton is constructed in accordance with a formula which may be stated as follows:

The height of one vertical wall of the carton 20 below the line along which the cross partitions are hinged thereto plus the width of the cross partitions is equal to the height of the other vertical wall of the carton below the line along which the cross partitions are hinged thereto plus 25 the width of the two cushion-forming bottom sections of the carton, the combined width of said bottom sections being greater than the width of the cross partitions.

When constructed in accordance with this formula it is possible to collapse the carton along the base of the higher of said walls, based on the line of attachment thereto of the cross partitions. This type of folding, which has been impossible 30 heretofore in the case of cushion cartons, is highly advantageous from many standpoints, including the lack of necessity for folding the cross partitions along their central portion, as is done 35 in collapsing the Troyk carton.

Since there are two vertical walls to an egg 40 carton, the formula may be met by attaching the cross partitions to the front wall at a higher point than the rear wall, or by attaching the cross partitions to the rear wall at a higher point than 45 the front wall, the carton being collapsed along the base of the higher wall.

As shown in the drawings, the carton is formed 50 from a blank of material which is suitably cut and scored to provide, in the order named, a cover-locking strip 10 having hooks 11 along the free edge thereof, a cover 12 hinged to the top of a rear wall 13, a bottom section composed of a rear section 14 and a front section 15, a front wall 16, cross partitions 17 hinged to the top 55 thereof by means of integral triangular hinged

portions 18, and an attaching strip 19 hinged to the opposite or free edges of the cross partitions by means of triangular hinges 20. In the bottom sections 14 and 15 and adjacent the cross partitions 17 are provided slots 21 and 22, respectively. The cross partitions are rotated into vertical position about the hinged portions 18 and 20 and hooks 23 on the lower rear portion of the cross partitions are engaged in slots 21 of the rear section 10 of the bottom, while hooks 24 on the lower portion of the front part of the cross partitions are engaged in slots 22 of the front section of the bottom portion, whereby the bottom portion is suspended in substantially inverted V-shape to provide a cushion for eggs carried by the carton.

Between the hooks 23 and 24 the lower parts of the cross partitions are cut away, the cut-away portions of each cross partition appearing on the top of the next adjacent cross partition in the form of upwardly extending projections 25 which act as supports for the cover 12 when the latter is in closed position.

It will be observed that the bottom sections 14 and 15 are wider than the distance between the front and rear walls but that the combined width of such sections is less than the width of the bottom section of the carton described in Troyk Patent; No. 1,766,155. In erected position the bottom sections extend upwardly and inwardly to 30 form a cushion bottom of substantially inverted V-shape, the sections of the bottom extending substantially in planes rather than being curved. In certain instances it may be found desirable to impart a curve to the bottom sections but in the 35 modification shown in the drawings the sections are flat or uncurved in order to save material.

In manufacture of the embodiment shown in Figs. 1 to 4, the blank from which the carton is produced is suitably cut and scored, and then 40 folded along a score line between the front wall 16 and the front bottom section 15. A line of glue is applied to the inner face of the attaching strip 19 and the latter is pressed against the rear wall, 45 adhering thereto, thus completing the formation of the collapsed carton. From a collapsed condition the carton may be erected by means of a setting-up mechanism such as that disclosed in Burger Reissue Patent, No. 18,547.

The elements of the structure are proportioned 50 so as to comply with the following formula: The height of the rear wall from the line along which the cross partitions are hinged thereto to the bottom of the carton plus the width of the rear bottom section plus the width of the front bottom section is equal to the height of the front wall plus the width of the cross partitions.

I find that it is possible to construct the carton so as to comply with this formula by securing the attaching strip at such a position that the hinged 60 portions of the cross partitions by which the cross partitions are hinged to the rear wall are lower than the hinged portions of the cross partitions by which the latter are attached to the front wall. In other words, the cross partitions are mounted 65 to the front and rear walls on a bias. It will be seen that the exact proportion of the elements of the construction may be varied, so long as the formula prescribed is adhered to. For instance, if it is desired to increase the width of the bottom portion, as by increasing the width of the bottom sections 14 and 15, the carton may be made 70 to comply with the formula prescribed by decreasing the distance between the bottom of the rear wall and the point at which the cross partitions are hinged thereto. That is, the cross parti-

tions are positioned on a still greater bias, the exact extent of which will depend upon the increase in the width of the bottom of the carton. As the cross partitions are secured to the rear wall at a point below the top of the front wall, the cross partitions are cut in such a manner that the lower portions are of less height than the front portions, the extra material preferably being allowed to remain on the upper portion of the cross partitions and projections 26. These projections serve to 10 make it less obvious that the partitions are hinged at different heights adjacent the front and rear walls, respectively.

In the embodiment shown in Figs. 5 and 6 the carton is constructed in a similar manner to the 15 carton described hereinbefore, except that the bias of the carton is oppositely disposed. That is, the elements of the carton are so proportioned and constructed as to comply with the following formula: The height of the rear wall below the 20 point at which the cross partitions are pivoted thereto plus the width of the cross partitions is equal to the height of the front wall plus the width of the front bottom section plus the width of the rear bottom section. In this embodiment, 25 the carton is collapsed along the score line between the rear bottom section and the rear wall and the score line between the triangular projections 18 by which the cross partitions are hinged to the front wall and the front wall 16. 30

That is, the cross partitions are biased in such a manner that a plane between the rear hinged portions and the front hinged portions will extend downwardly toward the front wall.

In either of the cartons described hereinbefore 35 there is the advantage that very little paper is required. In a modification which extensive tests have shown to be satisfactory from the standpoints of carrying capacity and safety, the bottom of the carton is substantially $\frac{3}{4}$ of an inch 40 less in width than the width of cartons constructed in accordance with the Troyk patent, for example. In the case of a carton 11 inches in length, it will be seen that over 8 square inches material is saved. Furthermore, the construction permits folding of the carton into collapsed condition without scoring or folding the cross partitions, which scoring and folding has the disadvantage of weakening the cross partition structure and permitting the carton to be compressed 50 more readily than in the absence of such scorings. An additional advantage of my improved carton is its ease of set-up or erection. Since the bottom sections are not curved and do not come together below their apex, the bottom sections may 55 be engaged with the hooks on the lower portion of the cross partitions quite readily, as by pressing the apex of the carton into engagement with said hooks with the hand of the operator.

The variations to which my invention is susceptible are intended to be included in the appended claims.

I claim:

1. A cellular carton composed of a blank cut, scored and folded to form front and rear walls, 65 a cushion bottom of substantially V-shape, and cross partitions hinged to the front and rear walls, the height of one of the vertical walls below the point at which the cross partitions are hinged thereto plus the width of the cross partitions 70 being equal to the height of the other of said walls below the point at which said cross partitions are hinged thereto plus the width of said bottom section.

2. A cellular carton comprising front and rear 75

walls, a bottom section of substantially inverted V-shape, cross partitions secured to said walls, the point of securement to one of said walls being lower than the point of securement to the other of said walls, and said cross partitions being shorter adjacent the wall to which said point of attachment is lower.

3. A cellular carton, comprising front and rear walls, cross partitions hingedly connected to said walls, and a bottom section wider than said cross partitions, the height of one of said walls below the point at which the cross partitions are hinged thereto plus the width of the cross partitions being equal to the height of the other of said walls below the point at which the cross partitions are hinged thereto plus the width of said bottom section, and said bottom section being drawn up along its central portion and engaged with said cross partitions to form a cushion bottom for said carton.

4. A carton, comprising front and rear walls, cross partitions hinged to said walls, at different heights, and a bottom section wider than said cross partitions, the height of the rear wall below the point to which the cross partitions are attached plus the width of the cross partitions being equal to the height of said front wall below the point at which the cross partitions are hinged, plus the width of the bottom section, said carton being foldable into collapsed condition along a score line at the base of the rear wall.

5. A cellular carton comprising front and rear walls, cross partitions hinged to said walls, a bottom section wider than said cross partitions, said section having a central score line and means for engaging said cross partitions to maintain said section in inverted V-shape when the carton is in erected condition, the height of one of said walls below the point at which the cross partitions are hinged plus the width of the cross partitions being equal to the heights of the other of said walls below the point at which the cross partitions are hinged thereto plus the width of said bottom section.

45. 6. A cellular carton of the type described, comprising a blank cut scored and folded to form a rear wall extending downwardly in substantially a vertical plane to a surface upon which the carton is positioned, a bottom section of substantially inverted V-formation having one edge joined to the lower edge of said rear wall and extending upwardly therefrom in cushion forming position, a front wall joined to the opposite edge of said bottom section and extending upwardly therefrom in substantially a vertical plane, cross partitions hinged to said front wall, an attaching strip hinged to the opposite sides of said cross partitions and being secured to said rear wall at such position that the height of one of said walls below the

point at which the cross partitions are hinged plus the width of the cross partition will equal the height of the other of said walls below the point at which the cross partitions are hinged thereto plus the width of said bottom section, whereby said carton may be collapsed along the bottom of one of said walls and along the other of said walls at the line said cross partitions are hinged thereto.

7. A cellular carton of the type described, comprising a blank cut scored and folded to form a rear wall extending downwardly in substantially plane formation, a bottom section joined to the lower edge of said rear wall, a front wall joined to the opposite edge of said bottom section and extending upwardly therefrom in substantially plane formation, cross partitions hinged to said front wall, and an attaching strip hinged to the opposite sides of said cross partitions and being secured at said rear wall at such position that the height of one of said walls below the point at which the cross partitions are hinged will be greater than the height of the other of said walls below the point at which said cross partitions are hinged, the height of one of said walls below the point at which the cross partitions are hinged plus the width of the cross partitions being equal to the height of the other of said walls below the point at which the cross partitions are hinged thereto plus the width of said bottom section, whereby said carton may be collapsed along the bottom of one of said walls and along the other of said walls at the line said cross partitions are hinged thereto.

8. A cellular carton of the type described, comprising a blank cut scored and folded to form a rear wall extending downwardly in substantially plane formation to a surface upon which the carton is positioned, a bottom section of substantially inverted V formation having one edge joined to the lower portion of said rear wall and extending upwardly therefrom in cushion forming position, a front wall joined to the opposite edge of said bottom section and extending upwardly therefrom in substantially plane formation, cross partitions hinged to said front wall, an attaching strip hinged to the opposite sides of said cross partitions and being secured to said rear wall at such position that the height of one of said walls below the point at which the cross partitions are hinged plus the width of the cross partitions will equal the height of the other of said walls below the point at which the cross partitions are hinged thereto plus the width of said inverted V-shaped bottom section, and means supported by said cross partitions for engaging said bottom sections and maintaining the latter in cushion forming position.

RAYMOND STONE.
